UNITED STATES PATENT OFFICE.

JAMES CORNELIUS, OF RIDGEWOOD, NEW JERSEY.

TABLET-MACHINE.

SPECIFICATION forming part of Letters Patent No. 603,231, dated April 26, 1898.

Application filed June 30, 1897. Serial No. 642,973. (No model.)

To all whom it may concern:

Be it known that I, JAMES CORNELIUS, of Ridgewood, in the county of Bergen and State of New Jersey, have invented a new and Improved Tablet-Machine, of which the following is a full, clear, and exact description.

The object of the invention is to provide a new and improved tablet-machine which is simple and durable in construction, very effective in operation, and arranged for ready adjustment to produce tablets of any desired shape and thickness and to conveniently discharge the finished product from the forcing-die of the plunger.

15 The invention consists of certain parts and details and combinations of the same, as will be fully described hereinafter and then pointed out in the claims.

Reference is to be had to the accompanying drawings, forming a part of this specification, in which similar characters of reference indicate corresponding parts in all the figures.

Figure 1 is a side elevation of the improvement. Fig. 2 is a like view of the same with 25 parts in a different position. Fig. 3 is a front elevation of the same. Fig. 4 is a sectional plan view of part of the improvement on the line 4-4 of Fig. 3. Fig. 5 is a transverse section of the improvement, and Fig. 6 is a sectional plan view of part of the improvement 30 on the line 6-6 of Fig. 3.

The improved tablet-machine is provided with a base A, supporting a post or standard A', carrying a table B, open at the front and 35 adapted to contain the material to be formed into the tablet. In the table B is formed an opening for the reception of the die C, held in place in the table by a set-screw C', engaging an annular recess in the die, the latter 40 being flush with the top surface of the table, as plainly indicated in Fig. 5. The die is provided with a central bore, which may be of any desired shape, it being understood that dies with various forms of bores may be inserted in the table B and fastened therein by 45 the set-screw C' to form tablets of various shapes. Into the bore of the die C is adapted to pass the upper end of an anvil D, forming a bottom for the die-bore to hold the material in the bore during the time it is compressed, as hereinafter more fully described.

The anvil D is fitted to slide vertically in a

suitable bearing A², projecting from the standard A' and containing a friction-washer D', engaging the anvil to hold the latter in 55 position unless forced up or down, as herein-after described. The lower end of the anvil D is adapted to rest on the spiral cam-surface E', formed on top of the cam E, provided with a vertically-disposed central pin E², 60 mounted to turn in suitable bearings in the base A. The cam E is provided with an outwardly-extending arm E³, adapted to be taken hold of by the operator to turn the cam, so as to bring the spiral cam-surface at different 65 points in contact with the under side of the anvil D to raise the latter or to permit the same to move downward, according to the direction in which the cam E is turned.

In the arm E³ is held a set-screw E⁴, adapted 70 to abut against a stop-pin F, removably inserted into one of a series of apertures A³, formed in the base A in the segment of a circle, the center of which is in the center of the pin E², as will be readily understood by reference to Fig. 4.

75 By the arrangement described the forward swinging movement of the handle E³ is limited by the set-screw E⁴ striking against the stop-pin F, and it is evident that more or less 80 turning motion can be given to the cam E by adjusting the stop-pin F correspondingly in the apertures A³. The handle E³ preferably projects from the side of the cam at the highest edge thereof, as shown in the drawings, 85 so that when the handle E³ is turned from the left to the right away from the pin F until the handle E³ stands at right angles to the base A then the lowest portion of the cam-surface E' is directly under the lower end of 90 the anvil D, as illustrated in Fig. 2, and the upper end of the said anvil is now a suitable distance below the lower end of the die C. When the handle E³, however, is in the forward position, with the set-screw E⁴ abutting 95 against the pin F, the anvil D is in a raised position and extends with its upper end into the lower portion of the die C.

When the anvil is in an uppermost position and forms the bottom for the bore of the 100 die C, the said remaining portion of the bore is filled with the material for forming the tablet, and this amount of material is regulated in quantity by the distance that the upper

end of the anvil passes into the said die C. Now as the cam-surface E' gages this upward movement of the die and the movement of the cam is limited by the said set-screws E⁴ striking the stop-pin F it is evident that by adjusting the stop-pin F in a corresponding aperture and moving the handle forward until the set-screw E⁴ strikes the pin the quantity of the material is gaged, and the operator is enabled to regulate the amount at will by the adjustment referred to.

A plunger G is adapted to pass into the die C from above to compress the material in the die, and this plunger G is secured by a set-screw G' in the stock H, fitted to slide vertically in a suitable bearing A⁴, forming part of the standard A'. The rear face of the stock H is formed with rack-teeth H', in mesh with a gear-wheel I, mounted to turn in a bore in the standard A', and forming part of a handle I', secured to one outer end of the said gear-wheel. The other end of the gear-wheel is engaged by a washer I³ to prevent the lateral displacement of the gear-wheel in its bearing. On the hub of the handle I' is formed a cam-surface I², adapted to engage the upper end of a rod J, fitted to slide loosely in the bearing A⁵, forming part of the standard A'. A spring J' presses the said rod J, so as to hold the same normally in an uppermost position. The lower end of the rod J is pivotally connected with an arm K of a bell-crank lever mounted to turn on a pin K', secured to the bearing A², previously referred to. The other arm K² of the bell-crank lever extends upwardly and is provided with a pusher-arm K³, adapted to rest against the rear of the anvil D when the latter is in an uppermost position and to pass over the said anvil when the latter is in a lowermost position to push the tablet carried on the upper end of the said anvil off the same, so that the tablet is discharged from the machine.

The operation is as follows: When the several parts are in the position illustrated in Fig. 1, the anvil D is in an uppermost position—that is, it extends into the die C—and the plunger G is likewise in an uppermost position above the table B, so as to permit of filling the die with the material to be formed into the tablet. When this has been done, the operator swings the handle I' over into the position shown in Fig. 2, whereby the gear-wheel I is turned and the stock H with the plunger G is moved downward and the lower end of the said plunger passes into the die and compresses the material therein against the anvil D, which forms the bottom for the die. When this has been done, the operator takes hold of the handle E³ and swings the same to the right into the position shown in Fig. 2 to bring the lowest point of the cam-surface E' under the anvil D. As soon as this has been done the operator presses the handle I' still farther downward into a lowermost forward position, so as to push the formed tablet, together with the an-

vil D, downward until the tablet is out of the die below the table B, as shown in Fig. 5, it being understood that the anvil D slides downward in its bearing A² and is finally held therein by the friction-washer when the handle I' is in its lowermost forward position. When this has been done, the operator swings the handle I' back to its former position and in doing so brings the cam-face I² over the upper end of the rod J, so that the spring J' thereof now forces the rod J upward, whereby a swinging motion is given to the bell-crank lever and the pusher-arm K³ thereof moves forward to push the tablet off from the upper end of the anvil D. It then immediately recedes back to its former position, as the cam-face I² passes off the upper end of the rod J previous to the arm I' reaching its final position, as shown in Fig. 1. The operator now again takes hold of the handle E³ and turns the cam E back to its former position—that is, until the set-screw E⁴ strikes the stop F, so that the anvil D is raised into its uppermost position. The above-described operation is then repeated—that is, the die is again filled with the material and the arm I' is swung forward to compress the material so as to form the tablet.

It will be seen that by the arrangement described the operator is enabled to readily adjust the anvil D in the die, according to the amount of material desired to be pressed into the tablet, and the operator is also enabled to readily exchange the die, anvil, and plunger for other different shapes whenever desired.

Having thus fully described my invention, I claim as new and desire to secure by Letters Patent—

1. A tablet-machine comprising a die, an anvil adapted to pass into the said die, means for raising and lowering the said anvil to move the latter into the die and permit the same to pass out of the die, a plunger adapted to pass into and out of the die, to press the material therein into a tablet and to force the latter with the anvil out of the die for discharging the finished tablet, and a device for removing the tablet from the anvil on the receding of the said plunger from the die, substantially as shown and described.

2. A tablet-machine, comprising a die, an anvil adapted to pass into said die, means for raising and lowering the anvil, a reciprocating plunger for pressing the material in the die to form a tablet and force the latter with the anvil out of the die, and a swinging arm controlled by the plunger - operating means for removing the tablet from the end of the anvil, substantially as described.

3. A tablet-machine comprising a die, an anvil adapted to pass into the said die, means for raising and lowering the said anvil to move the latter into the die and permit the same to pass out of the die, a plunger adapted to pass into and out of the die, to press the material therein into a tablet and to force the latter with the anvil out of the die for dis-

charging the finished tablet, and a device for removing the tablet from the anvil and controlled from the means for operating the said plunger, substantially as shown and described.

4. A tablet-machine provided with a die, an anvil adapted to pass into and out of the said die, and a manually-operated cam for controlling the movement of the said anvil, substantially as shown and described.

5. A tablet-machine provided with a manually-operated cam mounted to turn and formed with a spiral cam-surface, substantially as shown and described.

15 6. A tablet-machine provided with a cam mounted to be turned and formed with a spiral cam-surface, and adjustable means for limiting the turning motion of the said cam, as set forth.

20 7. A tablet-machine provided with a die, an anvil adapted to pass into and out of the said die, and a cam mounted below the anvil and having its axis eccentric to the axis of the said anvil, the said cam having a spiral face 55 engaged by the end of the said anvil, substantially as shown and described.

8. A tablet-machine provided with a die, an anvil adapted to pass into and out of the said die, a cam mounted to be turned and having 30 its axis eccentric to the axis of the said anvil, the said cam having a spiral face engaged by the said anvil, and an adjustable stop-pin for limiting the turning motion of the said cam, substantially as shown and described.

35 9. A tablet-machine comprising a die, a 70 slideable plunger for the said die, an anvil adapted to pass into and form a bottom for the said die, and a cam mounted to be turned and engaging the said anvil to regulate the thickness of the tablet to be formed in the die, substantially as shown and described.

10. A tablet-machine provided with an arm mounted to swing for discharging the formed tablet from the machine, a spring-pressed rod connected with the said arm, and a cam for 45 pressing the said rod to impart a swinging motion to the same in one direction, the return movement of the arm being accomplished by the spring of the arm, substantially as shown and described.

50 11. A tablet-machine provided with a slideable anvil, means for raising and lowering the said anvil, and a swinging arm adapted to swing over the same on lowering the anvil below the said arm, substantially as shown and described.

12. A tablet-machine, provided with an anvil, a bearing in which the anvil is fitted to slide, and a friction device for holding the anvil in place in the bearing, substantially as 60 shown and described.

13. In a tablet-machine, the combination with a die, a plunger, means for operating the plunger, and a reciprocating anvil, of a swinging and spring-actuated arm controlled by the 65 plunger-operating means for removing the tablet from the anvil, substantially as described.

14. In a tablet-machine, the combination with a die, a plunger, a plunger-operating lever having a cam-surface, and a reciprocating anvil, of a sliding and spring-pressed rod having one end engaging the said cam-surface, a bell-crank lever to one member of which the 75 said rod is connected, and a pusher-arm secured to the other member of the bell-crank lever, substantially as described.
